UNITED STATES PATENT OFFICE.

JOHANNES ROBERT CARL AUGUST, OF HALIFAX, ENGLAND.

MUFFLE FURNACE.

1,415,424.

Specification of Letters Patent.

Patented May 9, 1922.

Application filed May 8, 1920. Serial No. 379,995.

To all whom it may concern:

Be it known that I, JOHANNES ROBERT CARL AUGUST, subject of the King of Great Britain, residing in Halifax, in the county 5 of York and Kingdom of England, have invented certain new and useful Improvements in or Relating to Muffle Furnaces, of which the following is a specification.

This invention has reference to rotary 10 muffle furnaces of the type in which the muffle or barrel is concentrically mounted and supported within a rotary heating chamber or furnace so that while both revolve together spaces are left between them, and 15 in which the electrically produced heat is made use of to heat the muffle.

The invention will be understood from the following description reference being had to the accompanying drawings, in which:— 20 Figure 1 is a longitudinal section of my furnace, and

Figure 2 is a similar view showing a modification.

Referring to Figure 1, the rotary furnace 25 comprises a cylindrical metal casing 20 lined inside with fire clay slabs 21, and extends in a horizontal or slightly inclined direction, and the barrel or muffle 22 is supported concentrically inside the casing 20. At one end, 30 the rotary casing has a circular concentric aperture 25, and the barrel 22 which may be made of fire clay is closed at the inner end, while inside this barrel 22 and fairly closely fitting it, is a movable container 49 to receive the articles which are to be subjected 35 to heat treatment. This container 49 which may be of metal is inserted through the central aperture 25 of the rotary casing 20, and through the open end of the barrel 22, and 40 the open end of this container is provided with a removable gas tight cover or closure 27. The outer end of the container which may be enlarged a little as shown, extends a little beyond the end of the cylindrical casing 20, and its cover may consist of a plate 27 secured by nuts and set pins to the flanged outer end of the container 49, and may carry on its inner side by means of rods, an inner plate or diaphragm 27^x which abuts against 45 the shoulder at the junction between the container proper and its enlarged end. By the removal of this cover, the articles to be subjected to heat treatment, can be readily introduced and afterwards withdrawn. 50 The barrel 22 is fixedly supported inside the

rotary furnace chamber 20 so as to revolve with it. The outer circumference of the casing forms trackways for carrying rollers 30, and the said casing 20 together with the barrel 22, is rotated by a worm 28 meshing 60 with a worm wheel 29 on the external circumference of the said casing. The metallic bands 31 cooperating with the carrying rollers 30 resist longitudinal play of the rotary furnace. The disposition of the parts 65 enables the container 49 to be withdrawn at any time required without disturbing the outer casing 20 or the barrel 22. The electric heater is shown at 46.

This consists of a heating coil of wire 70 wound round the barrel 22 so as to be supported thereby and designed to receive a current of electricity, and to produce by resistance heating effects. These heating coils 46 are insulated from the outer casing 75 20 by a supplementary casing 22' of fireclay and by a surrounding casing of insulating material 50 such as asbestos, mineral wool or the like, both around the barrel 22 and at the inner end thereof, that is to say in the 80 annular space between the casing 20 and the barrel 22, and in the space between the end of the barrel and the casing. The insulating material 50 keeps the coil spaced apart without danger of accidental displacement. For 85 supplying current to the electric heater 46 there is arranged upon the outside of the outer casing 20 at the end, contact rings 48, and bearing against these contact rings are brushes (not shown) carried by suitable 90 supports. The heater 46 is connected through the wires 51 with the outer rings 48. Cooperating with these parts is a switch board which is connected to the source of electrical supply.

The furnace shown in Figure 2 is similar to that described in Figure 1, except that in Figure 2 the electric heater 47 consists of some substance in a powdered granulated or compound state capable of producing by resistance heating effects, as for instance ferro-silicon, of suitable compositions and resistances. 100 20 as before is the outer metallic casing lined inside the fire clay slabs 21, 22 the barrel or muffle supported concentrically, 25 the circular concentric aperture, 49 the metal container, 27, 27^x the cover thereof, 30 the carrying rollers, 28 the worm and 29 the worm wheel. In this disposition of the furnace, a supplementary fire clay cyl- 105 110

inder 52 is interposed in the annular space between the barrel 22 and the outer casing 20 so as to form an annular chamber between the barrel 22 and the said cylinder 52, in which chamber the powdered material 47 is packed, and an annular chamber between the barrel 22 and the outer casing 20 in which chamber insulating material 50 is inserted such as asbestos, mineral wool or the like, so as to insulate the heating unit 47 and the cylinder 52 from the outer casing 20. The chamber in which the heating unit is placed, is completely closed on all sides, as will be noted from the drawing by the cylindrical portion of 52 and the ends thereof and by the barrel 22 so that the powdered material cannot escape, and the heat must necessarily be absorbed by the barrel 22. For supplying current to the heating unit 47, there is arranged on the outer casing 20 at the end, contact rings 48 and bearing against these contact rings are brushes. The heating unit 47 is connected through wires 51 with the outer rings 48, one of these wires supplying current to the heating unit and the other being the return wire.

To operate the furnace, the articles to be carburized for the purpose of case hardening them, or be otherwise subjected to heat treatment, are introduced into the container 49, and the cover 27, 27* is closed. The current is turned on, the furnace set into rotation, and the heating unit is cut into circuit, whereby the interior of the container is raised to the requisite temperature.

I declare that what I claim is:—

1. A rotary furnace of the rotary barrel type, formed by the combination of a rotary chamber closed at one end, and having a central aperture at the other, a muffle or barrel concentrically mounted inside the said rotary chamber so that while both revolve together an annular space is left between them, an electric heater located in the said space, and insulated from the said rotary chamber, and a removable container inserted closed end first into the barrel through the said central aperture, while

the open end which is closed by a detachable cover is left projecting.

2. A rotary furnace of the rotary barrel type formed by the combination of a rotary chamber closed at one end, and having a central aperture at the other, a muffle or barrel concentrically mounted inside the said rotary chamber so that while both will revolve together, an annular space is left between them, a supplementary fire clay cylinder interposed in the annular space between the barrel and the outer chamber so as to form an inner annular chamber between it and the barrel, and an outer annular chamber between it and the outer chamber, an electric heating unit composed of powdered material inserted in the inner annular chamber and insulating material inserted in the outer one.

3. A rotary furnace of the rotary barrel type, formed by the combination of a rotary chamber closed at one end and having a central aperture at the other end, a muffle or barrel concentrically mounted inside of the said rotary chamber so that while both revolve together, an annular space is left between them, a heater located in said space, and a removable container inserted closed end first into the barrel through the aperture, and a removable cover closing the open end of the container.

4. A rotary furnace of the rotary barrel type, formed of a rotary chamber closed at one end and having a central aperture at the other end, a removable container inserted closed end first into the aperture, an electric heater surrounding the container, and a detachable cover closing the open end of the container.

In witness whereof, I have hereunto signed my name this 19th day of April, 1920, in the presence of two subscribing witnesses.

JOHANNES ROBERT CARL AUGUST.
